Inventor:
William G. Houskeeper.

by *W. Beatty, Atty.*

UNITED STATES PATENT OFFICE.

WILLIAM G. HOUSKEEPER, OF NEW YORK, N. Y., ASSIGNOR TO WESTERN ELECTRIC COMPANY, INCORPORATED, OF NEW YORK, N. Y., A CORPORATION OF NEW YORK.

VACUUM INSULATOR AND ITS ASSEMBLY.

Application filed November 26, 1920. Serial No. 428,454.

To all whom it may concern:

Be it known that I, WILLIAM G. Hous-
KEEPER, a citizen of the United States, re-
siding at New York, in the county of New
York, State of New York, have invented
certain new and useful Improvements in
Vacuum Insulators and Their Assembly, of
which the following is a full, clear, concise,
and exact description.

10 This invention relates to devices for in-
sulating the conductors of high voltage, high
frequency circuits and pertains more
especially to an insulating device adapted
for use in conducting through the base of
15 a high power vacuum tube the lead wires
of the grid and anode electrodes.

In employing a vacuum tube in certain
installations, particularly in high voltage,
high frequency circuits, it is necessary to
20 provide special means for preventing corona
effects along the grid and anode lead wires
and discharges from said lead wires to the
base of the tube or to the lead wires of the
cathode. Heretofore, attempts have been
25 made to prevent these effects by surrounding
the lead wires with bodies of insulating ma-
terial extending through the disc forming
a portion of the base of the tube. However,
30 the dielectric losses due to the high voltage,
high frequency currents produced sufficient
heating of the bodies of insulating material
to quickly destroy their insulating property
and thus render the tube inoperative.

It is an object of this invention to provide
35 an insulator for use in the base of a high
power vacuum tube for conducting the grid
and anode lead wires therethrough which
will effectively prevent discharges from and
40 corona effects along said lead wires and in
which there will be no injurious heating of
the dielectric.

A further object of the invention is to pro-
vide an insulator for general use in high
voltage, high frequency circuits which is
45 simple in construction and highly efficient
in operation.

To accomplish these objects and to im-
prove generally upon insulating devices, this

invention comprises an evacuated closed ves-
sel through which is passed a conductor, the
50 evacuated space providing the necessary in-
sulator. The vessel may be mounted
wherever it is desired to utilize its insulating
property and be included in an electric cir-
cuit by connecting the ends of the conductor 55
with the conductors of the circuit. For, ex-
ample, the vessel may be mounted in the
base of a vacuum tube, with one end con-
nected to the lead wire of an electrode of the
60 tube and the other to a contact member.

Other objects and features of this invention
will be apparent from the following
specification and appended claims.

This invention will be better understood
65 by reference to the following specification
and accompanying drawing wherein Figure 1
1 discloses a vacuum tube equipped with in-
sulators made in accordance with the invention
and Figure 2 discloses the insulator 70
adapted for general use.

In Figure 1 the vacuum tube comprises
the bulb 19 having a cylindrical neck 11 and
a re-entrant stem 12. Encircling the stem
12 is a metallic collar 13 equipped with the
75 supports 14 extending into the interior of
the bulb. Carried by the supports 14 is the
cylindrical anode 15 from which are sup-
ported the blocks 16 of insulating material
between which are mounted the grid 17 and 80
cathode 18 according to the manner dis-
closed in applicant's U. S. Patent No. 1,536,-
855 issued May 5, 1925.

Extending through the stem 12 to the
end of the neck 11 are the tubular members
19 and 20, the inner ends of which are in 85
communication with the interior of the bulb.
Arranged in said tubular members are the
grid and anode lead wires 21 and 22 to
which are sealed the outer ends of the said
tubular members. Mounted on the neck 11
90 of the bulb and cemented thereto is a metal-
lic shell 23 in the lower end of which is
carried the disc 24 of insulating material
having a groove 24a in its periphery. In the
disc are provided two apertures wherein are 95
arranged the insulators 25 which are cement-

ed to the disc. Each of these insulators comprises a vessel of insulating material, preferably glass, which vessel is cylindrical at its midportion and which tapers conically toward its ends. A flange 26 is provided on the vessel whereby it may be located in its aperture relative to the disc. A conductor 27 extends through this vessel and is sealed in the ends thereof, one end thereof being adapted to be joined to the lead wire of the grid or anode. On the exposed end of the vessel is provided a contact thimble 28 which is electrically connected with the conductor 27. The vessel 25 is evacuated through tip 29 which is sealed off in a well-known manner. The disc 24 is also provided with contact members 30 which preferably have apertures therethrough to receive the lead wires 31 of the cathode 18, said lead wires being enclosed in the glass tubes 31^a.

In the assembling of the base and bulb, the insulators 25 and the contact members 30 are first associated with the disc 24. The disc is then placed in the shell 23 adjacent the edge of the end thereof which is to be cemented to the neck of the bulb with the uncapped ends of the vessels 25 projecting beyond said edge. The shell is then so placed relative to the bulb as to bring the disc into the approximate position which it will occupy after complete assembly, the lead wires 31 are threaded through the contact members 30 and the exposed ends of the conductors 27 are joined to the ends of the lead wires 21 and 22 of the anode and grid electrodes. Then the shell 23 is slipped along the disc 20 and onto the neck 11 to which it is cemented, after which the lower end of the shell is spun into the groove 24^a in the periphery of the disc 24. The lead wires 31 of the cathode 18 are then soldered to the contact members 30, after which they are flushed off even with the ends of the contact members. This method of assembly assures that those portions of the lead wires of the grid and anode electrodes between the ends of the tubular members 19 and 20 and the inner ends of the insulators 25 will be approximately straight.

In Figure 2 wherein the insulator is disclosed for general use 32 designates a support or member from which a conductor is to be insulated, for example, a partition or the like. The vessel 33 is of the same configuration as 25 and is provided with a similar flange 34. The conductor 35 passes through the vessel and is sealed into the outer ends thereof. On either end of the vessel are provided caps 36 which are permanently joined to the vessel and which are electrically connected with the conductor 35. These caps are provided with means for attaching electric wires thereto, preferably by having an aperture therein through which

the wire may be passed and held in place by the set screw 37.

These insulators, when used in the bases of vacuum tubes, allow the tubes to be operated in high voltage, high frequency circuits. The evacuated condition of the vessel prevents the high voltage high frequency circuits from causing a heating of the dielectric and thus preserves the insulating property thereof.

It is to be understood that changes may be made in the structural features of this device without in any way departing from the spirit of the invention as set forth in the appended claims.

What is claimed is:

1. In an electric discharge device, a base, a unitary evacuated vessel of insulating material carried by said base, said vessel tapering conically toward the ends thereof, a leading-in wire of an electrode of the tube passing through said vessel, a cap mounted on one of said ends, and an electrical connection between said leading in wire and said cap.

2. In a base for electric discharge devices, a disc, a unitary evacuated vessel of insulating material mounted in said disc, an electrical conductor passing through said vessel, said conductor comprising a portion of the leading-in wire of an electrode of a vacuum tube, a cap mounted on said vessel, and an electrical connection between said conductor and said cap.

3. In a base for electric discharge devices, a disc having an aperture therein, a unitary evacuated vessel having a cylindrical portion and conical ends arranged with its cylindrical portion in said aperture, an electrical conductor passing through said vessel and sealed into the ends of the conical portions, said conductor comprising a portion of the leading-in wire of an electrode of a vacuum tube, a cap mounted on one end of said vessel, and an electrical connection between said cap and said conductor.

4. In a base for electric discharge devices, a disc having an aperture therein, a unitary evacuated vessel having a cylindrical mid-portion and conical ends arranged with its cylindrical portion in said aperture, a flange on said cylindrical portion to engage said disc to position said vessel relative to said disc, an electrical conductor passing through said vessel and sealed into the ends of the conical portions, said conductor comprising a portion of the leading-in wire for an electrode of a vacuum tube, a cap mounted on one end of said vessel, and an electrical connection between said cap and said conductor.

5. A device of the character described comprising a unitary evacuated vessel of insulating material, an electrical conductor passing through and sealed in a wall of said

vessel, a cap carried by said vessel, said cap being electrically connected with said conductor and forming a terminal.

6. A device of the character described, comprising a unitary evacuated vessel of insulating material, said vessel having a substantially cylindrical member having conical ends, a flange around the midportion of

said vessel, a metallic cap on one of said conical ends and a conductor passing ¹⁰ through said vessel, said conductor being electrically connected to said cap.

In witness whereof, I hereunto subscribe my name this 18th day of November A. D., 1920.

WILLIAM G. HOUSKEEPER.
